US00D532312S

(12) **United States Design Patent** (10) **Patent No.:** **US D532,312 S**
(45) **Date of Patent:** **** Nov. 21, 2006**

(54) **CONTAINER BODY**

(75) Inventors: **Simon M. Conway**, Burlington, WI (US); **Kristopher W. Gerulski**, Racine, WI (US); **Daniel Perez**, Chicago, IL (US); **Todd A. Zeilinger**, Chicago, IL (US)

(73) Assignee: **S.C. Johnson & Son, Inc.**, Racine, WI (US)

(**) Term: **14 Years**

(21) Appl. No.: **29/240,441**

(22) Filed: **Oct. 13, 2005**

(51) **LOC (8) Cl. 09-01**

(52) **U.S. Cl. D9/538; D9/551; D9/556**

(58) **Field of Classification Search** D9/516, D9/522, 530, 537-539, 541-542, 549-551, D9/556, 558, 560, 563-564, 569, 571-574, D9/763, 772-773, 776, 779; 215/379, 381-382, 215/385; 220/660, 662, 669

(57) **CLAIM**

The ornamental design for a container body, as shown and described herein.

DESCRIPTION

FIG. 1 is a top, front, right side perspective view of an ornamental design for a container body according to the present invention;

FIG. 2 is a front elevational view thereof, the rear elevational view being identical;

FIG. 3 is a right side elevational view thereof, the left side elevational view being identical;

FIG. 4 is a top plan view thereof; and,

FIG. 5 is a bottom plan view thereof.

The broken lines shown in the drawings are for illustrative purposes only and form no part of the claimed design.
